UNITED STATES PATENT OFFICE.

JOHN A. STAPLES, OF NEWBURGH, NEW YORK, ASSIGNOR TO STAPLES & HANFORD COMPANY, OF NEWBURGH, NEW YORK, A CORPORATION OF NEW JERSEY.

SPRINGWORK.

No. 798,752.

Specification of Letters Patent.

Patented Sept. 5, 1905.

Application filed November 15, 1901. Serial No. 82,386.

To all whom it may concern:

Be it known that I, JOHN A. STAPLES, a citizen of the United States, residing at Newburgh, in the county of Orange and State of New York, have invented certain new and useful Improvements in Springwork, of which the following is a specification.

In springwork as heretofore constructed the spring-supports, generally in the form of hanging or drop wires, have been provided with corrugations or bends usually in a vertical plane and the adjustability of the springs along these supports or the points at which the springs were set limited to the points at which the bends or deflections occurred. For example, when the deflections or bends were in the form of eyes or of loops the points of attaching the springs were limited to these loops, and when corrugations were employed the points of attachment were limited to the top and bottom points thereof.

The object of my present invention is to improve upon this prior form of construction and to provide an organization wherein the range of adjustment of the springs along the length of the supporting-wires is increased to include all points upon their horizontal portions, whether within the frame with which they are associated or upon the end portions resting on the frame. I accomplish this object by providing an organization comprising supporting-wires without bends or corrugations in their horizontal portions and intersecting or crossing wires or keys having bends or deflections to receive the straight supporting-wires and coil-springs uniting with the wires at their crossing by a rotary movement.

My invention is illustrated in the accompanying figures of drawings, which show various forms of its embodiment, and in which—

Figure 1 is a cross-section of a frame, showing a straight or plain supporting-wire and intersecting wires with springs supported at the points of intersection. Fig. 2 is a detail perspective view showing the spring and wires at the crossing-point, the intersecting wire having a form of bend or corrugation that may be employed. Fig. 3 is a detail perspective view similar to Fig. 2, but showing a different form of bend or corrugation in the intersecting wire. Fig. 4 is a side view showing a spring in elevation and the straight supporting-wire in section and an intersecting wire provided with a different form of bend

or deflection. Fig. 5 is a view similar to that shown in Fig. 4, the view being taken upon the opposite side; and Fig. 6 is a perspective view showing a spring and the intersecting or crossing wire arranged on top of the straight supporting-wire.

The supporting-wires A are of suitable length to pass from one side to the other of the frame of the chair-seat, bed-bottom, or other article of furniture, and each has an interior horizontal portion *a*, which is approximately as long as the measurement of the opening of the frame A', and preferably the ends are bent upwardly to provide a drop and are then provided with horizontal end portions *a'* and finished with means for attachment to the frame, preferably by providing points which may be driven into the frame, as shown in Fig. 1, though, of course, it is understood that the ends may be finished off in the form of eyes for receiving nails or screws to secure the supports in place. The supports are thus in the form of hanging or drop wires, and their main or body portions *a*, which are normally within the opening of the frame when the parts are assembled, constitute the means for supporting the usual interior springs. The supports A may be of any form or configuration and may be attached to the frame at any place and in any manner, though the construction which I have here disclosed is best adapted for practical work.

The intersecting wires or keys B are provided with suitable bends or deflections *b*, arranged at their points of crossing with the supports A, and these corrugations or bends may be made in any suitable manner and in any suitable form which will provide a depth such that when one of the intersecting wires is associated with a supporting-wire the necessary space will be provided between the wires for the small end of the spring to be interlaced by rotating the same, the wire of the spring passing into the space between the respective horizontal planes of the crossing wires, under one and over the other, when the spring has been given a full rotation and wedging against the wires to firmly bind the parts together.

The bends or corrugations in the cross wires or keys B may be made in any suitable form, the only essential feature being that they shall be of such depth as to permit one or more of the coils of the springs to be intro-

duced between the supporting-wire and the cross-key. As shown in Fig. 2, the bend or loop is of substantially uniform curvature, while in the form shown in Fig. 3 it is substantially angular in outline, and in Figs. 5 and 6 it is substantially U-shaped or has its ends nearer together to more nearly resemble a closed loop or eye. The various forms here shown illustrate embodiments of this feature of the invention, which of course may be greatly varied in form and configuration. In all instances, however, the loop or bend is of such depth as to position the body portion b' of the crossing or intersecting wire in a different horizontal plane from the supporting-wire and to leave sufficient space between the bodies of the two wires to receive one or more of the coils of the springs.

In the organizations above described the intersecting or crossing wires are placed below the supporting-wires. It is obvious that this arrangement may be reversed and that the intersecting wire may be placed above the supporting-wire, the bends or loops of the intersecting wires then resting upon the straight supporting-wires, as shown in Fig. 6, and providing the space for the introduction of one or more of the coils of the spring, as before.

It will be observed that when the wires are assembled, whether the intersecting wires be above or below the supporting-wires, the depth of the bends or deflections b provide the necessary space to receive one or more of the coils at the small ends of the springs C, which are interlaced or interwoven by rotating the springs, the spiral formation of the strands or coils bringing pressure upon the wires to bind them together and to bind the springs thereto, as is well understood in the art. In order to more effectually provide against displacement along the supports, the latter may be roughened or barbed, as shown at a^2 in Fig. 6, as an auxiliary means, if desired.

The leading ends c of the springs C are slightly larger than the following two or three coils, as c' and c^2 , or are somewhat tangential to these coils, which are preferably of substan-

tially the same size or diameter, (and slightly smaller than the width of the bends or corrugations.) By this construction the leading ends more easily engage the wires and the springs are more readily threaded in place. When the springs are rotated, the lower coil or coils (the number varying according to the depth of the bends) will ride up the sides or faces of the bends and bring increased pressure thereon, which will slightly spring the straight supporting-wire to tightly wedge into the apex of the offset or bend. For example, in Figs. 2, 3, and 6 the interwoven portions of the springs rest upon and bind against the straight wires and the opposite portions of the bends of the intersecting wires. In Figs. 4 and 5 this action is the same, and the interwoven coils tend to spring the opposite sides of the loop together, whereby a very stringent binding action on the supporting-wires is obtained. The tempered metal of the coils will bend the loops of the soft metal of the supports to a very perceptible degree.

It will be understood that the words "straight" and "plain" are employed herein in connection with the supporting-wires to refer to and mean that their horizontal portions are not provided with bends or corrugations and of course include hanging or drop wires without bends or corrugations in their horizontal portions.

Having described my invention, I claim as new and desire to secure by Letters Patent—

In springwork, the combination of springs each having its leading end tangential and slightly beyond the succeeding coils, supporting-wires having plain horizontal portions, intersecting wires having bends to receive the supporting-wires, the bends being normally wider than the initial coils of the springs and of sufficient depth to receive the same and bind them against the crossing wires.

In testimony whereof I affix my signature in presence of two witnesses.

JOHN A. STAPLES.
